UNITED STATES PATENT OFFICE.

LYNN W. BUCK, OF SPRINGFIELD, VERMONT.

SHUTTLE-OPERATING MECHANISM.

SPECIFICATION forming part of Letters Patent No. 363,724, dated May 24, 1887.

Application filed September 6, 1886. Serial No. 212,808. (No model.)

To all whom it may concern:

Be it known that I, LYNN W. BUCK, of Springfield, in the county of Windsor and State of Vermont, have invented an Improvement 5 in Shuttle-Operating Mechanisms for Looms, of which the following is a full, clear, and exact description.

Hitherto the sweep-stick which connects the picker-stick of a loom to its operating arm 10 or lever has been connected to the picker-stick by means of leather straps or loops, which give a lost motion or permit a certain rebound or freedom of action to the picker-stick, which is essential to the satisfactory operation of the loom; but, owing to the elasticity of the leather and its lack of strength, the said leather connections have to be frequently renewed, which entails considerable labor and loss of time.

20 The object of my invention is to overcome this objection and to make an all-wood or an all-metal connection of the sweep-stick with the picker-stick, and yet retain the freedom of action or rebound of the picker-stick incident 25 to the ordinary leather loop-connections.

To this end my invention consists, principally, of an independent support for the sweep-stick, the latter being formed with a slot for the reception of the picker-stick, which permits the picker-stick to move through a short 30 space independently of the sweep-stick.

The invention also consists of the construction, arrangement, and combination of parts, all as hereinafter described and claimed.

35 Reference is to be had to the accompanying drawings, forming a part of this specification, in which similar letters of reference indicate corresponding parts in all the figures.

Figure 1 is a detailed side elevation of a part 40 of a loom, showing the picker-stick, sweep-stick, and the arm or stick for supporting the outer end thereof. Fig. 2 is a sectional elevation of the same, taken on the line xx of Fig. 1; and Fig. 3 is a sectional plan view 45 taken on the line yy of Fig. 1.

A represents the picker-stick, B the sweep-stick, and C the independent support for the sweep-stick. These parts are all, by preference, of wood. The picker-stick A and the

supporting-stick C are both pivoted upon the 50 gudgeon D of the arm E of the frame of the loom, the same being held upon the gudgeon by a pin or key, a . The sweep-stick B is formed with a slot, F, through which the picker-stick passes, and in which the picker-stick has a considerable play, so that the picker-stick may have a considerable motion independent of the sweep-stick, as will be understood from Fig. 3. The support C is connected to the sweep-stick B by a pivot pin or bolt, b , 55 to and it swings freely on the gudgeon D, with the movement of the sweep-stick, and there are several holes, c , formed in the support C, so that the sweep-stick may be raised or lowered to regulate the throw of the picker-stick. 60 By this means of supporting the sweep-stick and connecting it with the picker-stick, an all-wood or all-metal connection may be effected, and the picker-stick also given the required freedom of movement or action independent of the sweep-stick which the leather connections permit, and the connection is as durable as the loom and cannot get out of repair; besides, the sweep may be raised or lowered, if desired, by simply placing the pin b in 65 one or the other of the holes c .

Having thus described my invention, what I claim as new, and desire to secure by Letters Patent, is—

1. The sweep stick B, in combination with 80 an independent support, C, said sweep-stick being formed with a slot in which the picker-stick is held, substantially as described.

2. The sweep-stick B, formed with slot F, through which the picker-stick passes, in combination with the picker-stick and the pivotal support C, the slot F being made larger than the picker-stick to permit independent movement of the picker-stick, substantially as described. 85

3. The picker-stick A and the sweep-stick B, in combination with the support C, formed with several holes, c , substantially as and for the purposes described. 90
